DESIGN FOR A TABLE

Chauncey E. Waltman, Chicago, Ill., assignor to
Sandel Manufacturing Co., Chicago, Ill., a cor-
poration of Illinois

Application October 3, 1942, Serial No. 108,418

Term of patent 7 years

To all whom it may concern:

Be it known that I, Chauncey E. Waltman, a citizen of the United States and resident of Chicago, in the county of Cook and State of Illinois, have invented a new, original, and ornamental Design for a Table, of which the following is a specification, reference being had to the accompanying drawing, forming a part thereof.

The figure is a view in perspective of the table, showing my new design.

The dominant feature of my design comprises the table having a pair of glass panels arranged

on a standard adjacent the upper edge thereof, said panels being substantially parallel to each other and spaced from each other, said standard extending through said panels, the upper portion of said standard terminating in a substantially rounded knob and extending above the upper surface of the upper panel, all as shown.

I claim:

The ornamental design for a table, substantially as shown and described.

CHAUNCEY E. WALTMAN.
